CLAIM

The ornamental design for a cosmetics case, as shown and described.

DESCRIPTION

FIG. 1 is a front perspective view of a cosmetics case showing my new design, shown in a closed position of use; FIG. 2 is a front perspective view of the cosmetics case, shown in an open position, shown in an environment of use with exemplary pans;

FIG. 3 is a rear view of the cosmetics case;

FIG. 4 is a front view thereof;

FIG. 5 is a top view thereof;

FIG. 6 is a right side view thereof;

FIG. 7 is a bottom view thereof; and,

FIG. 8 is a left side view thereof.

In the drawings, stippled areas illustrate light emitting diodes that have a contrast in appearance.

In the drawings, broken lines illustrate environmental subject matter of exemplary pans and form no part of the claimed design.
